EXPRESS CONTAINER TYPE CARGO
AIRPLANE

Harlan D. Fowler, Whittier, Calif.

Application April 17, 1945, Serial No. 588,865

7 Claims. (Cl. 244—118)

1

This invention relates to a cargo airplane having the following general characteristics: A balanced streamlined design fore and aft of the wing; removable cargo containers when in place end to end in tandem forming part of the fuselage streamlined contour, and these preferably all positioned forward of the wing; such containers being removable and replaceable in a lateral horizontal direction from either side, or vertically, as desired; centrally controlled means to lock the containers in position on the fuselage platform, and auxiliary manual locking means individually operated for the several containers; landing gear supporting the fuselage close to the ground, enabling the ship to come close inside or alongside a ramp, with the landing wheels under the ramp; a pusher propeller, preferably reversible, so that the ship can be moved up inside or alongside a ramp, and the propeller blades be reversed to back the ship out; and the propeller being mounted high, whereby adequate clearance is obtained for the propeller notwithstanding the fuselage is low to the ground.

Additional features reside in a novel air cooling system for the motors, which may be mounted within the fuselage aft of the cargo container section, thus contributing to the accessibility of the containers, and which motors, by virtue of a forced draft cooling system, may be left idling when loading or unloading the plane.

Another feature is the provision of a passageway for controls in the belly region of the fuselage, with access holes below for maintenance accessibility thereto.

More specifically, a feature of importance is the provision of tracks on the bed or platform of the fuselage on which rollers or casters on the cargo containers are movably supported.

A number of other novel features inherent in my concepts are disclosed as the description progresses, and many of the features indicated are susceptible of substitution by elements which are equivalent.

A broad object of my invention is to produce an express container type cargo airplane which embodies improvements over my U. S. Patent No. 1,992,941, granted March 5, 1935, for Airplane construction, and also over various co-pending applications.

Additional objects are to incorporate in such an improved airplane structure the features enumerated above, and others which will be disclosed.

Thus, the primary objects may be partially summarized as directed to the production of a cargo container type streamlined airplane with

motors mounted within the fuselage and coupled with pusher type propellers located aft, the fuselage design affording suitable air cooling ducts for the motors, the fuselage having a long nose section for removable cargo containers, and convenient accessibility to such containers from either side, and a landing gear supporting the fuselage low to the ground and in sufficient proximity to an adjacent loading ramp or ramps so that containers may be rolled from the airplane to the ramp or vice versa.

These, and other objects of the invention will become further apparent from the more detailed description which follows.

15 In the drawings:

Figure 1 is a perspective view of an airplane embodying my invention, in a loading dock.

Figure 2 is a side elevation of the airplane, with parts in section.

20 Figure 3 is a vertical cross section through the pilot's compartment, taken on the line 3—3 of Figure 2.

Figure 4 is a perspective view of one of the cargo containers forming an element of the airplane.

25 Figure 5 is an enlarged fragmentary side view, partly in section, showing the container locking elements, and taken generally along the line 5—5 of Figure 7.

30 Figure 6 is a top plan view of the assembly shown in Figure 5.

Figure 7 is a vertical section through one side of the fuselage platform, showing the track for the container rollers, and the locking mechanisms, taken along the line 7—7 of Figure 5.

35 Figure 7a is a fragmentary section taken on line 7a—7a of Figure 5.

Figure 8 is an enlarged fragmentary horizontal section through the engine compartment of the fuselage, and illustrating the air cooling ducts and carburetor intake ducts.

40 Figure 9 is a vertical section taken on the line 9—9 of Figure 8.

Figure 10 is a cross section taken on the line 10—10 of Figure 9.

45 Figure 11 is an enlarged cross section of the platform and belly region of the fuselage taken on the line 11—11 of Figure 2.

50 Figure 12 is a cross section taken on line 12—12 of Figure 11.

The airplane 20 comprises a fuselage 21, wing 22, tail control assembly 23, pusher type propeller 24 mounted aft of the tail assembly, engines 25 mounted within the fuselage, and a tri-

cycle type landing gear indicated as 26. The airplane is shown in a loading dock 27.

The airplane design is statically and aerodynamically balanced so that when the plane is on the ground the fuselage maintains the same attitude as in horizontal flight, and the landing gear is designed so that the fuselage platform carrying the cargo containers will be approximately in the same horizontal plane as the top 30 of the loading dock.

This dock may have an inclined ramp 31 leading to the level top 30. Also, the vertical support 32 nearest the loading edge 33 should be spaced away from such edge to provide room for the rear wheels 34 of the landing gear upon the top. The other details of construction of the dock can be conventional. Preferably complementary docks are employed, with a passage 35 therebetween substantially wide enough for entrance of the fuselage element of the airplane. The wing is above the dock, and the propeller is outside of it. Figure 1 illustrates the desired relationship between the plane and the loading dock when the plane is stationed for loading or unloading. By the use of the twin dock arrangement shown in Figure 1, containers can be rolled off the fuselage platform at one side, and other containers rolled from the opposite side onto the fuselage platform, thus providing continuous systematic movements of the containers. The same arrangement provides ease of loading and unloading bulk cargo at the rear doors, later described.

The landing gear 26 preferably comprises a small nose wheel or wheels 36, which may or may not be retractable and/or steerable, in addition to the large aft wheels 34. The latter are preferably carried by a retractile means 37, of any suitable design, intended to nest the wheels in the faired position shown at 34' when the airplane is in flight. The details of the wheel mountings are not part of my invention, the important thing being to observe the requirements necessary to maintain the relationship between plane and ground, and plane and loading dock illustrated and described. Inasmuch as the fuselage platform level may vary 10" more or less between empty and loaded condition, due to change in length of shock absorber struts in the landing gear, it is desirable that the elevation of the dock be at the approximate upper extreme of such fuselage positions.

The fuselage 21 includes a pilot's compartment 40 in the nose 41, a cargo container platform or bed 42 between the pilot's compartment and the leading edge of the wing 22, a central engine compartment 43, a bulk cargo compartment 44, and interchangeable cargo containers 45.

The pilot's compartment is accessible through a side door 50, and terminates at the rear in a bulkhead 51. In the bulkhead is a door 52 which is as large, or larger, than a door in the immediately adjacent cargo container, later described, which doors are substantially coincident so that the interior of the foremost container is accessible from the pilot's compartment to load or unload packages while the container is in place.

The platform or bed 42 may comprise a longitudinally corrugated deck 53 riveted to flanges 54a of transverse bulkhead members 54, which are in turn riveted to side spars 60 and to the inner wall of a double skin 62 spaced by bottom stiffeners 61. Transverse tracks 56 are secured to the deck and to the side spars 60. The tracks include flat rail elements 57 separated by elevated

dividing bars 58. Rollers of the containers hereinafter described are adapted to roll on the rails and to be guided and confined by the dividing bars 58. Each track accommodates the adjacent rollers of two proximately disposed containers. Thus, complementary spaced apart parallel rails of two track units are required for each container. The tracks extend laterally across the fuselage. The end structure 59 of each track 10 is suitably secured by bolts 63 to the frame structure of the fuselage including the side spars 60. The tracks preferably formed with arcuate depressions 64 at the four corner locations of each container space to locate the containers pending locking of the same or removal thereof from the platform.

To provide for the sliding of a container from the dock to the fuselage, an auxiliary hinged track 56' is provided between the edge of the dock to the side of the fuselage platform so that as the level of the fuselage changes with the loading conditions, the tracks will always be in continuous contact to the loading dock. When fully loaded the deck of the fuselage platform is normally about 36 inches from the static ground line, and since the depth of the platform is about 20 inches the clearance between the bottom of the fuselage and the said ground line is 16 inches.

The end of the auxiliary track is formed with a knobular member 56" adapted to be engaged in a complementary recess 64' in the track 64 so that the two tracks remain associated for movement of containers on or off the plane.

Locking devices 65 and 66 are in effect part of the general platform structure 42. Locking devices 65 are controlled simultaneously from a central location, as for example, from the pilot's compartment. The individual corner locks 66 are separately controlled. In order to understand the function of these locks, it is desirable to first describe the containers 45, which themselves form elements of the airplane fuselage.

The containers are preferably all alike for interchangeability, preferably of proportions about 45 70 inches high, 42 inches long, and 72 inches wide, the latter dimension being the approximate width of the fuselage platform. The general structure is disclosed in detail in my co-pending application Serial No. 469,890, now Patent No. 2,442,459. Such previous disclosure did not, however, embody rollers.

Each container comprises a framework 70 at each end, such framework being on the outside so that skin 71 enclosing the ends may form a smooth interior as this arrangement also favors a smooth interior at the sides and top. A rigid bottom (not here illustrated) is firmly interrelated with the frame. Horizontal frame elements 72 support a horizontal interior flexible partition (not shown) which divides the container into upper and lower compartments. The upper compartment is accessible through a side door 73, and the lower compartment is accessible through end doors 74. The side door 73 may be opened either while the container is on the airplane, or when it is off.

The lower corners of the frame structure are cut out as at 75 to provide recesses for rollers or casters 76 which are mounted on stub shafts 77 fixed to the frame or floor. These recesses are sufficiently high to accommodate parts of the locking mechanism above the rollers. The rollers are preferably within the end and side extremities of the containers.

The overall locking system 65 comprises a lock-

ing jack 85 at each end of each track. Each jack comprises a screw threaded section 86 operating in a threaded bore 87 at the end of the track. The threaded section 86 is on a stem 88 squared at its lower end as at 89 to key with a crank 90 which is clamped as by bolt 91 to a control rod 92 leading to a central control station such as the pilot's compartment. Mounted on the stem 88 is a T clamp 95 the vertical element of which has a bore 96 fitting over the stem between a head 97 and a shoulder 98. The "cross" of the T clamp is adapted to engage the peripheral surface of container rollers for holding the containers down on the tracks, or to be elevated for releasing the rollers.

Thus, shifting of the control rod 92 will simultaneously lock or unlock all of the T clamps to which the rod is attached. Ordinarily, there will be one control rod 92 on each side of the fuselage platform 42.

Supplementing and cooperating functionally with the locking jacks 85, the individually controlled locks 66 each comprise a plate 100 slidably positioned in a housing 101. The plate is formed with a vertical slot 102 having teeth forming a rack 103. A pinion 104 provided with a female wrench socket 105 can be rotated by a suitable wrench (not shown) to raise or lower the plate. Optionally, a spring 106 may frictionally tension the pinion.

When the plate is in elevated position, it tangentially engages the rollers of the adjacent cargo containers, and prevents lateral movement of these containers outwardly. When lowered, the rollers are freed to move out, providing the friction grip of the T clamps has been released.

Thus, for removing and replacing containers, the centrally controlled jacks 65 must be released, and then the individual plate locks 66 at the corners of containers selected for removal must be lowered on the side from which the containers are to be rolled. If a replacement container is to be rolled on from the opposite side, the plate locks at that side also must be lowered but the opposed plate locks should be raised to prevent the replacement container from rolling on through.

When all desired containers are in place, all plate locks are individually closed, and the centrally controlled jacks are clamped down, thus cooperatively securing the containers rigidly upon the deck.

As already noted, the bed of the fuselage forward of the wing, in the cargo container section, is corrugated and has approximately 14 feet open space in which to receive the containers. Aft of the wing, there is preferably the large compartment 44 with a flat plywood floor 111, the compartment being accessible through a door 112 large enough to pass an extra cargo container 45. Bulk cargo, or an extra container, or both, may be stowed in this compartment 44.

The large door 112 is preferably duplicated on the opposite side of the plane so that cargo containers or bulk cargo may be unloaded from one side and loaded in from the other side.

In the normal stationary ground attitude, the tail assembly 23 is elevated, and the pusher propeller 24 is mounted at the end of the tail assembly, so that the propeller has a material clearance above the ground. This propeller is preferably of a reversible type, such constructions being well known, so that the airplane may be backed under its own power out of a loading dock.

The engines 25 are located in the engine compartment 43, and propeller shafts 120 deliver

power to the propeller 24, through a conventional gear box 121. The high mounting of the engines and the overhead propeller shafts contribute several advantages to the airplane structure. Ample room is thus provided for the retractable landing gear, there is no obstruction in the rear bulk cargo compartment, and the high mounting of the propeller is facilitated. Moreover, either dual or single motors may be employed with this type of engine installation and power delivery with a single pusher propeller without altering the airplane design.

A tail skid 125, with a dolly wheel 126, depends from the tail assembly. This skid ordinarily does not touch the ground, but is primarily to afford protection to the propeller if the tail should fall.

An important feature of the airplane is the design of the fuselage and its relation to the engines. The engines are mounted within the fore and aft extremities of the wing, contributing to the general balance of the ship. The upper section of the fuselage is elevated from the leading edge of the wing rearwardly and a substantial distance above the upper contour of the forwardly located containers. The engines are supported on suitable framework 127, comprising the wing main spar 127a, a companion beam 127b, and longitudinal members 127c, and may be readily installed or removed from above, upon removal of an engine cowling 128 which conforms to the fuselage patterns.

This cowling is formed with a central port 130, and spaced ports 131, into which certain air ducts directly open. These include main air ducts 132 for cooling the engines, and subsidiary air ducts 133 for supplying air to the carburetors 134. The main air ducts 132 pass air to the engine radiators, such for example, as oil radiators 135 and prestone radiators 136, and thence continue to discharge ports 137 in the upper surface of the fuselage just aft of the engine cowling, the discharge being regulated by vanes 138. These vanes are vertical to the line of flight when opened, the vane shafts running fore and aft.

The nose section of the fuselage being of less height than the central section, affords unobstructed air intakes for the purposes described.

Auxiliary fans, or equivalent devices 140, may be located in the main air ducts, primarily to cause necessary cooling air circulation when the engines are idling on the ground.

I provide a control duct 150 in the belly section, secured to the bulkheads 54 and the bottom skin 62 for housing the various control elements 55 such as those for the power plants, propeller pitch, tail surfaces, ailerons and flaps, and landing gear. This duct preferably extends from the pilot's compartment to the propeller. It preferably has a top opening 151, either continuous or broken, for passage of cables, etc. to controlled elements, and a plurality of access ports 152 in the bottom normally closed by plates 153 removably secured to the skin 62, as by spring locked Dzus fasteners well known in the art.

In a plane of the approximate dimensions suggested in this description, the plates would preferably be about 8" or 10" square, and spaced about 7 feet apart.

By way of example, but not of limitation, an airplane embodying the principles of my invention may advantageously employ the following general proportions: overall length 60 feet, wing span 70 feet, height to top of tail surface 16 feet from static ground line, width of fuselage in cargo section 6 feet, belly depth (Figure 11) 20

7 inches, height of containers 70 inches, height of fuselage aft of container section 107 inches, the container platform approximately 14 feet long, belly supported about 16 inches above static ground line when fully loaded.

My construction is readily adaptable to jet propulsion in place of the engines and propeller illustrated. The air ducts are conveniently situated for air intake for a jet engine, without disturbing the forward cargo arrangement.

Although I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent structures.

Having described my invention, what I claim as new and desire to secure by Letters Patent is:

1. An airplane comprising a balanced fuselage and wing combination in which the wing is located centrally of the fore and aft extremities of the fuselage, there being a propulsive section limited to a position aft of the wing, and a nose section of material length limited to a position extending forward from the wing and including a platform having structural bracing therebelow adapted to support in end to end alignment a plurality of cargo containers and said platform being devoid of any fixed obstructions forward of the wing to interfere with authorized removal laterally of cargo containers, tracks mounted laterally across said platform spaced apart the approximately length of a container, a plurality of cargo containers adapted to be shifted laterally and substantially horizontally onto or off of said platform without substantially elevating the containers above said platform, the containers having rollers supporting them upon said tracks, the containers being in end to end alignment and having a cross section conforming externally to the contour pattern of the forepart of the fuselage, and cooperating means on the containers and on the platform for releasably locking the containers in position upon the platform.

2. An airplane comprising a balanced fuselage and wing combination including a platform adapted to support in end to end alignment a plurality of cargo containers, a plurality of cargo containers adapted to be shifted laterally and substantially horizontally onto or off of said platform without substantially elevating the containers above said platform, the containers having rollers supporting them upon said platform, the containers being in end to end alignment and having a cross section conforming externally to the contour pattern of the forepart of the fuselage, and cooperating means on the containers and on the platform for releasably locking the containers in position upon said platform, said means including a plurality of locking devices controllable by a common member and said locking devices being engageable with a peripheral portion of said rollers, and supplementary locking devices individually controllable and being engageable with a different peripheral portion of said rollers.

3. An airplane comprising a balanced fuselage and wing combination including a platform adapted to support in end to end alignment a plurality of cargo containers, said platform being devoid of any fixed obstructions above the sides of said platform to interfere with authorized re-

moval laterally of cargo containers, tracks mounted laterally across said platform spaced apart the approximate length of a container, a plurality of cargo containers adapted to be shifted laterally and substantially horizontally onto or off of said platform without substantially elevating the containers above the platform, the containers having rollers supporting them upon said tracks, the containers being in end to end alignment and having a cross section conforming externally to the contour pattern of the forepart of the fuselage, and cooperating means on the containers and on the platform for releasably locking the containers in position upon the platform, said means including a plurality of locking devices controllable by a common member and said locking devices being engageable with a peripheral portion of said rollers, and supplementary locking devices individually controllable and being engageable with a different peripheral portion of said rollers.

4. An airplane comprising a balanced fuselage and wing combination in which the wing is located centrally of the fore and aft extremities of the fuselage, there being a tail section aft of the wing, and a nose section of material length extending forward from the wing and including a platform and a plurality of cargo containers adapted to be supported in end to end alignment on said platform, the containers having a cross section conforming externally to the contour pattern of the forepart of the fuselage, cooperating means on said containers and on said platform for releasably locking the containers in position upon the platform, motive power means mounted within the fuselage centrally thereof, a pusher propeller at the extreme rear of said fuselage, and power transmitting means between said power means and said propeller, landing gear for supporting the fuselage when on the ground, the fuselage of said airplane in horizontal flight and in stationary ground attitude comprising a substantially level container section of narrow depth, said container section having structural bracing thereon the underside, the upper portion of the fuselage adjacent to and aft of the wing being elevated above the top of said containers and incorporating air intakes having their entrances at the forward end of said elevation.

5. An airplane of the character described in claim 4 in which there is a frame structure within the central region of the fuselage but aft of the main spar of said wing, said motive power means being supported on said frame structure closely adjacent the top of the fuselage and at the point of balance of the parts relative to the wing, a cowling on said fuselage above said motive power means and said motive power means being accessible for installation or removal through said cowling.

6. An airplane comprising a balanced fuselage and wing combination including a platform adapted to support in end to end alignment a plurality of cargo containers, a plurality of cargo containers adapted to be shifted laterally and substantially horizontally onto or off of said platform without substantially elevating the containers above said platform, the containers having rollers supporting them upon said platform, the containers being in end to end alignment and having a cross section conforming externally to the contour pattern of the forepart of the fuselage, and cooperating means on the containers and on the platform for releasably locking the containers in position upon said platform, said

means including a plurality of locking devices controllable by a common member and said locking devices being engageable with said rollers at the upper side of the periphery for holding the rollers in downward position against the platform, and supplementary locking devices individually controllable and being engageable with said rollers at the outermost position horizontally of the periphery thereof thereby preventing lateral shift of the containers upon the platform. 5

7. An airplane comprising a balanced fuselage and wing combination and including a platform adapted to support a cargo container, said platform being devoid of any fixed obstructions above the sides of said platform to interfere with authorized removal laterally of a cargo container, a cargo container on said platform adapted to be shifted laterally and substantially horizontally onto or off of said platform without substantially elevating said container above said platform, and cooperating means on the container and on said platform for releasably locking the container in position upon said platform, said platform comprising a shallow belly structure and duct for engine and surface controls located within said belly structure and extending from a point for- 10 15 20 25

ward of said platform to a point adjacent the extreme end of the tail section.
